MAGNETO GENERATOR

Edward B. Nowosielski, Sidney, N. Y., assignor to
 Bendix Aviation Corporation, South Bend, Ind.,
 a corporation of Delaware

Application May 11, 1937, Serial No. 141,943

6 Claims. (Cl. 171—209)

The present invention relates to a magneto generator and more particularly to an ignition generator for multi-cylinder internal combustion engines.

5 It is an object of the present invention to provide a novel form of high tension magneto which is efficient and reliable although small and light for its output capacity.

10 It is another object to provide such a device which is capable of producing efficiently a large number of sparks for each revolution of the driving shaft.

15 It is a further object to provide such a device which employs a plurality of small fixed magnets, the flux from which is caused to combine and reciprocate through the core of a stationary coil a plurality of times for each revolution of a rotor.

20 It is another object to provide such a device which is readily adaptable for use in connection with engines having various numbers of cylinders.

25 It is another object to provide such a device which is completely enclosed and shielded in a substantially smooth and symmetrical casing.

30 It is another object to provide such a device in which the magnets and coil are stationary, the reversals of flux being secured by rotation of a comparatively light rotor, and the magnetic circuit through the coil being completed by magnetic conductors surrounding the coil, thus increasing the inductive effect thereon.

35 Further objects and advantages will be apparent from the following description taken in connection with the accompanying drawings in which:

Fig. 1 is a vertical substantially mid-sectional view of a preferred embodiment of the invention;

40 Fig. 2 is a section taken substantially on the line 2—2 of Fig. 1;

Fig. 3 is a section taken substantially on the line 3—3 of Fig. 1;

45 Fig. 4 is a detail in perspective of the elements forming the magnetic circuits of the device;

Fig. 5 is a detail in perspective of an element of the magnetic inductor;

Fig. 6 is a detail in perspective of one of the permanent magnets employed; and

50 Fig. 7 is a detail in perspective of one of the fixed pole pieces interposed between said magnets.

Referring first to Fig. 1 of the drawings, there is illustrated a generally cylindrical casing 1 comprising three chambers, namely a generator

chamber 2, a breaker mechanism chamber 3 and a distributor mechanism chamber 4.

Two groups 5 and 6 of circularly arranged arcuate permanent magnets (Fig. 4) are fixedly mounted in the ends of the generator chamber 2 with pole pieces 7 and 8 interposed between the adjacent like poles of the magnets 5 and 6, said pole pieces extending radially inward and being formed with arcuate surfaces 9 and 11. Pole pieces 7 and 8 of like polarity are connected by 10 bolts 12 traversing the end partitions 13 and 14 of the generator chamber for maintaining the parts in assembled relation.

The generator chamber is formed in two sections joined as indicated at 10, and an induction coil 15 is mounted in the central portion thereof, being rigidly held in position by the clamping action of the bolts 12.

A drive shaft 16 is journaled at 17 and 18 in the partitions 13, 14 and carries rigidly keyed 20 thereon in any suitable manner as indicated at 19 and 21 an inductor member comprising a laminated cylindrical core member 22 traversing the induction coil 15, and laminated circular pole members 23 and 24 fixed on the ends of the 25 core and having arcuate projections 27 and 28 adapted to cooperate with the pole pieces 7 and 8 of the permanent magnets. In the arrangement illustrated in Fig. 4, there are eight permanent magnets in each group 5 and 6 and accordingly eight fixed pole members 7 and 8 interposed therebetween. Each circular pole member 23 and 24 of the rotor has four projections 27 and 28 respectively, which projections of each pole member are accordingly adapted to 35 simultaneously cooperate with the fixed pole pieces of like polarity. The projections 27 of pole member 23 are staggered rotarily with respect to the projections 28 of pole member 24 whereby when the pole member 23 is in inductive 40 relation with the fixed pole pieces 7 of one polarity, the pole member 24 is in inductive relation with the fixed pole pieces 8 of the opposite polarity. Closed magnetic circuits are thus provided for the flux from all the permanent 45 magnets, said flux flowing in one direction through the core 22 of the rotor and returning through the exterior path formed by the bolts 12 surrounding the induction coil as indicated by the arrows in Fig. 4.

The breaker chamber 3 of casing 1 contains breaker mechanism indicated generally by numeral 29, and drive shaft 16 projects into said chamber and carries a cam 31 fixed thereon for operating the breaker mechanism. The breaker 55

mechanism is connected to the primary winding of the coil 15 by a conductor 32, and the breaker points are shunted by a suitable condenser 33 in the usual manner.

- 5 Distributor mechanism indicated generally by numeral 34 is mounted in the distributor chamber 4 of the casing and comprises a distributor rotor 35 journaled as indicated at 36 in the casing and provided with a conductor 37 electrically connected to a central electrode 38 and arranged to cooperate at its ends with a plurality of output electrodes 39 and 41. The central electrode 38 is connected by a conductor 42 with a high tension cable 43 coming from the secondary winding of the induction coil 15. The electrodes 38, 39 and 41 and conductor 42 are preferably molded in a cup 44 of suitable dielectric material which is retained in the chamber 4 by any suitable means as indicated at 45.
- 20 The distributor rotor 35 is actuated by the drive shaft 16 through reduction gearing of such ratio as to adapt the device for the particular engine installation contemplated. Thus, in the embodiment illustrated, the device is adapted for 25 the ignition of a fourteen-cylinder engine. There are accordingly seven electrodes 39 and seven electrodes 41, and gearing is provided whereby the distributor rotor is driven at a ratio of 4:7 with respect to the drive shaft. As here shown, 30 this is accomplished by mounting an external gear 46 on the drive shaft in position to mesh with an internal gear 47 journaled as indicated at 47' in the chamber 4 and fixed to the rotor 35 by means of a cap screw 48, the proper timing 35 relation between the gear and distributor rotor being secured by suitable means such as a dowel 49.

In the operation of the device, rotation of drive shaft 16 causes the inductor rotor 22, 23, 24 to 40 rotate therewith, causing the pole shoes 21, 28 thereof to cooperate alternately with the fixed pole pieces 7 and 8 of opposite polarity. The flux of the permanent magnets 5 and 6 is thus caused to reciprocate through the core 22 of the inductor member eight times during each revolution 45 of the drive shaft and thereby induce currents corresponding thereto in the coil 15, the magnetic circuits being completed through the bolts 12 surrounding the coil and thereby augmenting the inductive effect therein. The cam 31 operates the breaker mechanism 29 to open and close the 50 primary circuit of the coil in the usual manner, and the secondary impulses so generated are conducted by the cable 43 to the distributor rotor 35.

55 Since the rotor 35 is geared to make one revolution while the inductor is making one and three-quarters revolutions, there will be fourteen impulses generated for each revolution of the rotor, which accordingly serves to properly distribute 60 the same to the spark plugs of the engine to be ignited.

It will be readily understood that this arrangement is very flexible as respects adaptation for 65 various engine installations, since it is merely necessary to change the distributor cap and/or vary the ratio of the reduction gearing 46, 47 in order to use this device for the ignition of engines having various numbers of cylinders. The numbers of permanent magnets used may also 70 be varied widely without changing the basic design of the device, inasmuch as neither the magnets nor the coil rotate, the only rotating element being the inductor which is of simple design, symmetrical and easily balanced.

75 Although but one embodiment of the invention

has been shown and described in detail, it will be understood that other embodiments are possible and various changes may be made in the design and arrangement of the parts without departing from the spirit of the invention as defined in the claims appended hereto.

What is claimed is:

1. In a magneto, a sectional casing, a plurality of magnets arranged therein in spaced annular groups, an induction coil interposed between said groups coaxial therewith, a drive shaft traversing concentrically said coil and magnets, an inductor rotor fixed on said shaft arranged to conduct the flux from said magnets through said coil, and a plurality of bolts arranged about the periphery of the coil for unifying the casing and serving as a return path for the flux traversing the coil.

2. In a high tension ignition magneto for internal combustion engines, a plurality of arcuate magnets arranged in spaced annular groups with like poles adjacent, fixed pole pieces between said poles and extending inwardly therefrom, a fixed induction coil located between said groups of magnets coaxially therewith having a hollow core, and a rotary inductor of highly permeable material comprising a cylindrical portion traversing said core, and pole members at its ends arranged to cooperate with said fixed pole pieces.

3. In a high tension ignition magneto for internal combustion engines, a plurality of arcuate magnets arranged in spaced annular groups with like poles adjacent, fixed pole pieces between said poles and extending inwardly therefrom, a fixed induction coil located between said groups of magnets coaxially therewith having a hollow core, and a rotary inductor of highly permeable material comprising a cylindrical portion traversing said core and circular pole members at its ends having pole shoes arranged so that each pole member cooperates with a group of pole pieces of like polarity, the arrangement being such that the two pole members simultaneously cooperate with groups of pole pieces of opposite polarity.

4. In a high tension ignition magneto for internal combustion engines, a plurality of arcuate magnets arranged in a pair of coaxial spaced annular groups with like poles adjacent, fixed pole pieces between said poles and extending inwardly therefrom, a fixed induction coil located between said groups of magnets coaxially therewith having a hollow core, a rotary inductor of highly permeable material comprising a cylindrical portion traversing said core and circular pole members at its ends arranged to cooperate with said fixed pole pieces, and means forming a return path for the flux traversing the inductor.

5. In a high tension ignition magneto for internal combustion engines, a plurality of arcuate magnets arranged in a pair of coaxial spaced annular groups with like poles adjacent, fixed pole pieces between said poles and extending inwardly therefrom, a fixed induction coil located between said groups of magnets coaxially therewith having a hollow core, a rotary inductor of highly permeable material comprising a cylindrical portion traversing said core and circular pole members at its ends arranged to cooperate with said fixed pole pieces, and a plurality of bars of highly permeable material arranged peripherally to said coil connecting pairs of said pole pieces of like polarity in said groups.

6. In a high tension magneto generator, a casing comprising three substantially cylindrical

chambers arranged end to end, one chamber containing generating means including a coil, fixed magnets, and an inductor causing the flux from the magnets to reciprocate through the coil; 5 breaker means in the second chamber including a cam; distributor means in the third chamber including a rotor, a conductor traversing the

breaker chamber transmitting the output of the coil to the distributor mechanism, a shaft journaled in the casing carrying and rotating the inductor and cam, and gearing connecting the shaft to the distributor rotor for driving it in 5 timed relation to the inductor and cam.

EDWARD B. NOWOSIELSKI.
